AMPHIBIOUS VEHICLE

Gordon Y. W. Ow, 1604 Ihiloa Loop,
Honolulu, Hawaii 96821

Filed Nov. 29, 1972, Ser. No. 310,470

Term of patent 14 years

Int. Cl. D12—14, 06

U.S. Cl. D12—3

FIG. 1

FIG. 2

FIG. 3

FIG. 4

FIG. 1 is a side elevational view of an amphibious vehicle showing my new design, the opposite side being substantially a mirror image thereof;

FIG. 2 is a top plan view thereof;

FIG. 3 is a front elevational view thereof; and

FIG. 4 is a rear elevational view thereof.

I claim:

The ornamental design for an amphibious vehicle, as shown.
